Primary Examiner — Michael C Stout

Assistant Examiner — Melvin L Davis

(57) **CLAIM**

The ornamental design for a toy as shown and described.

DESCRIPTION

1. Toy

1.1 : Front

1.2 : Back

1.3 : Left

1.4 : Right

1.5 : Enlarged view of the upper part of the front view

1.6 : Enlarged view of the lower part of the front view

1.7 : Perspective view of the upper part of the front view

1.8 : Top

1.9 : Enlarged view of the upper part of the back view

1.10 : Enlarged view of the lower part of the back view

1.11 : Enlarged view of the upper part of the left view

1.12 : Enlarged view of the lower part of the left view

1.13 : Enlarged view of the upper part of the right view

1.14 : Enlarged view of the lower part of the right view

1.15 : Perspective view of the lower part of the front view

1.16 : Bottom

1.17 : Bottom view of the upper part of the front view

1.18 : Top view of the lower part of the front view

The purpose of this design product: this design is used for a toy; the design point of this design product is the shape; the picture or photo that best shows the main points of the design: Front view.

1 Claim, 18 Drawing Sheets
